United States Patent Office.

EDWARD WHYTE, OF PHILADELPHIA, PENNSYLVANIA.

Letters Patent No. 65,320, dated May 28, 1867.

IMPROVED APPARATUS FOR COOLING LIQUIDS ON DRAUGHT.

The Schedule referred to in these Letters Patent and making part of the same.

TO ALL WHOM IT MAY CONCERN:

Be it known that I, EDWARD WHYTE, of Philadelphia, in the county of Philadelphia, and State of Pennsylvania, have invented a new and useful Improvement in Means for Cooling Liquid while on Draught; and I do hereby declare that the following is a full, clear, and exact description of the construction and operation of the same, reference being had to the annexed drawings, making a part of this specification, and to the letters and figures of reference marked thereon.

The object of my invention consists in providing better and cheaper means than have heretofore been devised for cooling liquids while on draught, such as ale, beer, cider, wine, and the like. To this end I construct a cylinder, a cross-section of which is shown by Figure 1 of the drawings. It is usually about a foot in diameter and a foot in length, more or less, corresponding to the amount of liquid to be drawn. The ends of said cylinder are made of wood, iron, tin, or other suitable substance, and it is lined throughout with zinc. The sides of said cylinder are covered with felt, and bands of iron or wooden hoops are passed around the same to give protection thereto. I leave an opening in the upper side of this cylinder, as shown at letter A, on Figure 2, and I adjust a block to said opening covered with felt so as to render the cylinder nearly or altogether air-tight when I desire to do so. The block and felt covering the same are represented by B on both the figures. I sometimes place a covering of zinc on the upper side of this block and felt for the purpose of giving more firmness and stability thereto. In the interior of this cylinder I place another and smaller cylinder, usually made in the form represented by letter C, on fig. 1. In size it must correspond to the size of the main cylinder, preserving about the same relative proportions thereto as is shown on the drawings. At one end of this small cylinder I attach a conducting pipe, marked D, by which it is connected with the barrel or vessel from which the liquid is to be drawn, and at the opposite end thereof I attach a faucet, E. For the purpose of cleaning said cylinder I attach a cap, F, to the end thereof, with a screw, so that it may be easily taken off by unscrewing.

My device is operated as follows, namely: I remove the block that fills the opening A, and fill the main cylinder with ice, packing it closely around the small cylinder C. I sometimes mix charcoal, salt, or saw-dust with the ice to prevent it from melting. I then replace the block and thereby close the opening securely. The liquor passes from the barrel or other vessel through the conducting pipe D into the cylinder C, and is cooled ready to be drawn off through the faucet for use.

What I claim as my invention, and desire to secure by Letters Patent, is—

A cooler covered with felt, ice-chamber as described, opening A, block B, and cylinder C, constructed and operating substantially as specified.

EDWARD ^{bis} WHYTE.
